UNITED STATES PATENT OFFICE.

WILLIAM HENRY HANSELL, OF PHILADELPHIA, PENNSYLVANIA.

EGG-CASE FILLER.

SPECIFICATION forming part of Letters Patent No. 662,424, dated November 27, 1900.

Application filed June 21, 1900. Serial No. 21,030. (No model.)

To all whom it may concern:

Be it known that I, WILLIAM HENRY HANSELL, of the city and county of Philadelphia, in the State of Pennsylvania, have invented 5 an Improvement in Egg-Case Fillers, of which the following is a specification.

My invention has reference to egg-case fillers; and it consists of certain improvements which are fully set forth in the following 10 specification and shown in the accompanying drawings, which form a part thereof.

My invention has for its object the construction of an egg-case filler of cardboard or similar material which shall be cheaply made 15 in a condensed condition and which may be stretched out and form a substantially square or rectangular frame to produce a series of connected compartments of special shape, into which the eggs may be placed and packed for 20 shipment.

In carrying out my invention I form the filler of a series of superimposed strips of cardboard scored or weakened at intervals to insure bending at the proper places and in the 25 proper directions, said series of cardboard strips being cemented or fastened at intervals in such a manner that when the completed structure is stretched out the said strips of cardboard bend in such forms as to constitute a substantially square or rectangular cellular structure formed with a series of parallel rows of octagonal tubular compartments separated by the series of rows of tubular chambers having polygonal outlines of sub- 30 stantially rectangular form, with the two opposite sides thereof bent outward, forming a polygon of ten sides. This construction is such that the eggs are supported in the best possible manner to be shielded against break- 35 age. In these compartments having the hexagonal construction the egg is supported in eight points in the circumference, while in the case of those having the ten sides the egg is supported at six points; but the points of 40 support between the eggs of two adjacent rows diagonally considered are out of alinement, so as to reduce the possibility of breakage by direct pressure of one egg upon the other.

My invention will be better understood by 45 reference to the drawings, in which—

Figure 1 is a plan view of an egg-case filler embodying my improvements. Fig. 2 is an end elevation of same. Fig. 3 is a plan view of the filler when collapsed. Fig. 4 is an elevation of one of the strips of cardboard from 55 which the filler is made. Fig. 5 is an edge view thereof. Fig. 6 is an enlarged view of a portion of Fig. 1. Fig. 7 is a plan view of a modified form of my invention, and Fig. 8 is an edge view of the cardboard employed in Fig. 60 7 for one of the sections before being used in the process of complete construction.

The filler is designed to hold forty-two eggs, though the capacity may be increased or diminished to suit the desire of the manufacturer. Forty-two eggs, however, enable the case to be made square, and hence is the preferred number. The filler is composed of a series of strips of pasteboard or other soft or flexible material connected in pairs, said 70 strips being indicated at A B in Fig. 3. These strips are scored or weakened transversely at points C C at one side and at D D on the other side. They are united together by being pasted at intervals (indicated at e f') to connect, respectively, the parts marked E F. When this is done and the two sides are spread apart, an octagonal-shaped compartment will 75 be produced. Such a pair of cardboard strips will produce four octagonal compartments or 80 chambers connected by three walls F, made two-ply. A similar second pair of strips are arranged alongside of the first pair, and the two pairs are connected by having their walls I of the adjacent hexagonal compartments 85 cemented or fastened at i. This will produce in the completed structure eight octagonal compartments H and four polygonal compartments K, having irregular outlines composed of ten sides. By connecting six of such pairs 90 of strips together in the same manner and applying a single strip to the outside of the construction so formed we will have the construction illustrated in Fig. 1, comprising a filler of forty-two compartments, in which 95 there are twenty-four hexagonal-shaped compartments and eighteen of the other polygonal structures.

In Fig. 5 the manner of scoring or weakening the cardboard is indicated at the points 100

C D, and immediately above in Fig. 4 the application of the paste or cement is shown at *e i f*, the vertical solid shade-lines indicating the paste on one side and the vertical dotted shade-lines indicating the paste on the other side. Of course in building up this structure it is not essential that the paste shall be applied to both sides of the same strip; but in the actual construction paste will be employed on opposite sides to unite said opposite sides to corresponding parts of the adjacent strip to which it is to be united.

Referring to Fig. 6, the dotted circles indicate the eggs, and it will be seen that the eggs in compartments K are kept considerably separated from the eggs in compartment H by virtue of the fact that the egg in compartment K is received upon the corners *k* of the cardboard, while the eggs in compartments H are supported by the cardboard walls at *h* considerably to one side of or out of alignment with the corner *k*. In this manner there is considerable cushioning or elastic support, which greatly increases the safety of the transmission of the crated eggs. In those cases where the eggs are in two adjacent compartments H H and two adjacent compartments K K they are separated by walls of pasteboard of double thickness and are therefore in this manner protected against breakage. Any thrust of the eggs on the walls of their supporting-compartments which are not in a direct line from compartment H to compartment H or compartment K to compartment K will be more or less received by the elastic supporting-points *k* and *h*, which will reduce very largely the possibility of breakage even under the most disadvantageous conditions.

It will be seen from an examination of Fig. 1 that the completed filler when stretched out is composed of a series of transverse cardboard strips united together at intervals in their length and produce thereby a series of rows of hexagonal-shaped compartments H, separated by a series of rows of polygonal-shaped compartments having ten sides and producing the oppositely-directed corners *k*, pointing toward the interior of said ten-sided polygon compartments to directly support the eggs therein, the rows formed by the similar adjacent compartments being arranged at right angles to the length of the cardboard strips composing them.

In this construction the two strips A B when united and bent into shape constitute a section which will comprise a number of hexagonal compartments connected by straight parts. When a number of these sections are connected, they produce the structure illustrated in Fig. 1.

In place of using two cardboard strips A B in pairs in building up the filler I may employ a series of longer cardboard strips, each

65 folded over upon itself and pasted together

at intervals. Such a cardboard strip in folded condition is indicated in Fig. 8, and the hexagonal construction produced thereby is illustrated in Fig. 7, the compartments H and K in this instance being the same as the corresponding compartments in the construction shown in Fig. 1.

I do not confine myself to the particular length or manner of connecting the strips employed to form the cellular structure so long as a structure of the character illustrated in Fig. 1 is produced. Therefore while I prefer the manner of building up the structure herein set out I do not confine myself to the minor details thereof.

Having now described my invention, what I claim as new, and desire to secure by Letters Patent, is—

1. An egg-case filler formed of flexible material such as cardboard, comprising a series 85 of strips cemented at intervals in their length weakened at intervals on both sides and bent transversely to their length to form a series of rows of clearly-defined octagonal compartments, and a series of interposed rows of 90 clearly-defined polygonal-shaped compartments having ten flat sides and inwardly-projecting clearly-defined corners *k* as shown.

2. An egg-case filler consisting of a series 95 of sections united together, each section being composed of a series of octagonal compartments connected together by spacing strips and forming between them series of polygonal-shaped compartments having their side walls provided with inwardly-projecting 100 corners diagonally arranged.

3. An egg-case filler consisting of a series 105 of sections united together, each section being composed of a series of octagonal compartments connected together by spacing strips, and forming between the octagonal compartments of two adjacent sections polygonal compartments each having four inwardly-projecting corners *k* formed at weakened portions of the strips and in which the 110 distances between the corners diagonally measured are substantially equal.

4. An egg-case filler consisting of a series 115 of sections forming octagonal compartments united together, each section consisting of two strips of flexible material superimposed and united together at the extreme ends and at intervals in the length between the ends on sides of the octagonal and in which the strips between the united parts are scored or 120 weakened in opposite directions so that they may be separated or opened and bent outwardly at said parts to constitute octagonal-shaped compartments with clearly-defined outward free corners and forming between 125 them a series of polygonal-shaped compartments having their side walls provided with inwardly-projecting corners diagonally arranged.

5. As an article of manufacture, a collapsi- 130

ble egg-case filler formed in its expanded condition with a series of rows of octagonal-shaped compartments separated by a series of rows of polygonal-shaped compartments having their walls weakened to form inwardly-directed corners or shoulders at defined places when the collapsed filler is expanded.

In testimony of which invention I have hereunto set my hand.

WM. HENRY HANSELL.
